UNITED STATES PATENT OFFICE.

THOMAS H. LEARY, OF RICHMOND, VIRGINIA.

WINDOW-VENTILATOR.

1,136,541.

Specification of Letters Patent. Patented Apr. 20, 1915.

Application filed August 17, 1914. Serial No. 857,101.

To all whom it may concern:

Be it known that I, THOMAS H. LEARY, a citizen of the United States, residing in Richmond, in the county of Henrico and State of Virginia, have invented certain new and useful Improvements in Window-Ventilators, of which the following is a specification.

This invention relates to ventilators of the class in which a screen or deflector is adjustably applied to a window frame in such manner that when the window is open air may be freely admitted but it will be deflected while entering in such manner as to prevent direct drafts from passing to the inside of the room.

According to my invention I provide a window ventilator of such construction and I so apply it to the window that it may be set or adjusted to a position either on the inside or on the outside of the window frame in such manner that direct drafts are avoided and when set on the outside the entrance of rain is prevented.

In carrying out my invention I connect the ventilator with the sides or jambs of the window frame by slotted rods which are hinged to the ventilator and are crossed and pivotally connected with the window frame by means of pins provided with tightening nuts, the arrangement being such that when desired the ventilator may be set on either the inside or the outside of the window and may be held at any desired angle relatively thereto.

In the accompanying drawings, Figure 1 is a perspective view of the lower portion of a window with my improved ventilator applied thereto. Fig. 2 shows a vertical central section of the same with the ventilator set on the inside of the window. Fig. 3 is a similar view with the ventilator set on the outside thereof. Fig. 4 is a detail view in perspective showing the manner of pivotally connecting the ventilator supporting rods with the window frame. Fig. 5 is a perspective view illustrating a modification.

A ventilator made in accordance with my invention may be applied to windows of usual construction. In the drawings A indicates the side frames or jambs of the window, B the sill and C the lower sash. The ventilator D may be of any suitable construction and made of any suitable material.

As shown in Figs. 1, 2 and 3, it comprises a screen or deflector d having at opposite

ends wings or sides d' disposed at right angles to the body or deflector d. The ventilator is of substantially the same width as the window opening, as indicated in Fig. 1, but may be moved through the opening when desired.

The ventilator is connected with the window frame by slotted rods E arranged in pairs, each pair being pivotally connected with the sides of the ventilator at e and the two rods of each pair are crossed and are pivotally connected with the window frame by pins G projecting from base plates g attached to the jambs A. The outer ends of the pins G are threaded and receive tightening nuts g'.

Fig. 2 shows the ventilator arranged on the inside of the window, the lower sash being raised as shown. Air entering the window from the outside will be deflected upwardly, as indicated by the arrows, and the ventilator may be firmly held in position by the rods which are locked by the nuts g' when the proper adjustment has been given. Any desired adjustment may be given to the ventilator by moving the rods on the pins and tightening the nuts. If it is desired to set the ventilator on the outside the sash is raised sufficiently to permit the ventilator to be passed through the window opening and adjusted to the position shown in Fig. 3 and there locked by the nuts g'. When in this position air may enter in the manner indicated by the arrows, but rain is prevented from entering as is clear from an inspection of Fig. 3.

I may give various shapes to the ventilator and may construct it of different materials.

In Fig. 5 I have shown a ventilator consisting of a frame H glazed at h. In this construction the slotted rods E are pivotally connected with the ventilator by means of brackets i.

I claim as my invention:

1. The combination with a window frame of a ventilator, and means for attaching the same to the window frame whereby the ventilator may be adjustably held either on the inside or the outside of the window comprising rods pivotally connected with the ventilator at different points thereon, and an attachment to pivotally and slidably secure said rods to the window frame.

2. The combination with a window frame of a ventilator consisting of a screen or de-

deflector and end wings arranged at right angles to the deflector, and means for attaching the same to a window frame whereby the ventilator can be adjustably held either on the inside or outside of the window comprising crossed slotted rods pivotally connected with the ventilator at different points thereon and an attachment to pivotally and slid-

ably secure said slotted rods to the window frame.

In testimony whereof, I have hereunto ¹³ subscribed my name,

THOMAS H. LEARY.
